UNITED STATES PATENT OFFICE.

ERNEST H. FOSTER, OF DONGAN HILLS, NEW YORK, ASSIGNOR TO POWER SPECIALTY COMPANY, OF NEW YORK, N. Y., A CORPORATION OF NEW YORK.

SUPERHEATER.

1,347,086.

Specification of Letters Patent. Patented July 20, 1920.

Application filed January 16, 1919. Serial No. 271,866.

To all whom it may concern:

Be it known that I, ERNEST H. FOSTER, a citizen of the United States, residing at Dongan Hills, county of Richmond, and 6 State of New York, have invented certain new and useful Improvements in Superheaters, of which the following is a full, clear, and exact description.

The invention upon which the present application for Letters Patent is based is an improvement in the means for supporting superheaters designed and used with certain types of marine boilers.

In boilers of this general type it has been proposed to inclose the superheater in a casing which is superposed on that containing the boiler proper, and to employ baffles in connection with the boiler tubes to deflect the hot gases to a greater or less extent, so 15 that they may pass over the superheater tubes. In such cases, however, no adequate provision, so far as I am aware, has ever been proposed for properly supporting the superheater and sustaining its weight, which 20 is applicable to the ordinary or typical form 25 of boiler of this class.

By my improvement, however, I make such provision in a thoroughly practicable and economical manner, and by its use I 30 am enabled to gain ready access to the superheater at any time for purposes of replacement, regulation or repair. Said improvement in general terms consists in supporting the superheater in a casing above the boiler 35 space in a marine or cross drum boiler on beams resting upon the steam and water drum at one end and the upper headers of the boiler tubes at the other.

This invention is illustrated in the accompanying drawings, which are drawn to show the specific means which I have found best adapted to securing the support above described.

Figure 1 is a side elevation of the boiler and superheater with the sides of the casings removed.

Fig. 2 is an end view of the superheater on an enlarged scale.

Fig. 3 is a longitudinal section of the 50 superheater on line 3—3 of Fig. 2.

Fig. 4 is a cross section of the superheater on line 4—4 of Fig. 3.

Fig. 5 is an enlarged sectional detail of the header supports in the superheater, and

Fig. 6 is an enlarged view in side elevation and front section of the superheater.

Similar letters of reference in the several figures indicate corresponding parts.

The general character of the boiler to which the improvement is applicable and the 60 general nature of the support for the superheater proper are shown in Fig. 1, in which 1 indicates the boiler casing, 2 the inclined bank of tubes, 3 the steam and water drum, and 4 the casing supported over the boiler 65 tubes and inclosing the superheater.

By reference to Fig. 3 it will be seen that the superheater tubes 5 rest upon cross beams 6, suspended by rods 7 from upper beams 8. These upper and weight supporting beams are in turn supported by vertical beams 9, carried by beams 13, which latter are supported at one end by brackets 10 upon the cross steam and water drum 3, and at the other end by brackets 11 placed 75 upon the upper headers 12 of the boiler tubes.

The beams in such figures as 3 and 4 are shown as associated with asbestos linings 17, and the same material is also shown as 80 largely making up the walls of the combustion chamber proper, but this is usual in such cases and forms no part of the present improvement. The specific details of construction shown are not, furthermore, of 85 the essence of the invention and may be greatly varied.

The superheater headers 13 for example are secured in place by straps 14 secured around them and to a supporting bracket 80 15, as shown in Figs. 3 and 5. Any proper form of bracket may be used under the ends of the main supporting horizontal beams.

The above described support for a superheater in boilers of this type is an important 85 contribution to the art. It is not practicable, for example, to support the heavy superheaters on the boiler tubes or by means of the casing of either the superheater or the boiler tubes, but by the means described 100 a rigid support from the boiler foundations up is secured which maintains the superheater at all times in its proper position.

The baffling for this boiler and superheater may be of any proper character and 105 the other details of construction may be selected from the prior art.

In further explanation of the invention,

it may be stated that a superheater supported upon the boiler will partake of the motion of the latter and move in unison with it. This avoids straining of the pipe connection between the superheater and the boiler which would not be true in a system in which the superheater is supported wholly or in part from the boiler setting or casing. This is an important consideration in marine

10 boilers of the type herein described.

What I claim as my invention is:—

1. In a cross drum water tube boiler, the combination with main horizontal beams supported at one end upon the steam and 15 water drum, and at the other end upon the upper headers of the boiler tubes, of upper beams and vertical supports therefor resting on the said main horizontal beams, a

superheater suspended from the said upper beams and a casing inclosing the super- 20 heater as set forth.

2. In a cross drum water tube boiler of the kind herein described, the combination with main horizontal beams supported at one end by brackets upon the steam or water 25 drum, and at the other end by brackets upon the upper headers of the boiler tubes, of upper beams, vertical supports between the same and the main horizontal beams, a superheater supported by suspension rods 30 from the said upper beams and a casing inclosing said superheater.

In testimony whereof I hereunto affix my signature.

ERNEST H. FOSTER.
